WILLIAM W. LASKER, OF BROOKLYN, AND HAROLD R. RUSSELL, OF DOUGLASTON, NEW YORK, ASSIGNORS, BY MESNE ASSIGNMENTS, TO REMINGTON RAND INC., OF NEW YORK, N. Y., A CORPORATION OF DELAWARE

AUTOMATIC SELECTING BAR

Application filed September 17, 1926. Serial No. 136,075.

The present invention relates to card perforating mechanism for record cards, and more particularly to an automatic control for selective punch operation.

5 Some of the objects of the present invention are to provide a control for a card perforating machine through the operation of a typewriter, a bookkeeping machine, an adding machine, or any other separately functioning machine; to provide an automatically selective means for causing only certain predetermined columns of typewritten matter to be perforated on a record card; to provide means for periodically and automatically preventing and permitting the production of perforations during the operation of a separate controlling machine; to provide a multiple control device for perforating machines whereby any one of a 10 number of controls can be employed to produce respectively predetermined operations of the perforating machine; to provide a settable control for perforating machines whereby any one of a number of different group 15 perforations can be made in a record card or cards; to provide a selecting bar for a perforating machine having a plurality of universal controls differing in character; to provide a control means of multiple positions 20 arranged to be set to cause a predetermined perforating operation; and to provide other improvements as will hereinafter appear.

In the accompanying drawings, Fig. 1 represents a side elevation of a typewriter 25 equipped with one form of the present invention; Fig. 2 represents a detail of the same showing the selecting bar of the present invention in front elevation; Fig. 3 is a diagram of the control circuits; and Fig. 4 is a 30 diagram representing any one of the key control circuits.

Referring to the drawings, attention is first directed to Fig. 4 in order that a clear 35 understanding of the resulting function of the present invention may be had. In the present embodiment of the invention it is shown as arranged to control selectively the energization of a plurality of solenoids 10, one of which is in each control circuit and 40 for the purpose of simplified description,

Fig. 4 may be taken as a sample of such circuits. The energization of a solenoid 10 causes its core 11 to actuate a Bowden wire 11' to transmit motion to a pivoted bell crank 12 which actuates a plunger 13 to set a latch 14, against the tension of its return spring 15, in order to prevent movement of a punch 16 when the punch frame 17 and card registering plate 18 are moved upward relative to the punch 16. It may be said at this point, 55 that this punch mechanism is one unit of a complete card punching mechanism wherein latches, such as 14, are selectively set so that the respective punches, controlled by the set latches, function to perforate the card, while 60 those punches which are not held by said latches are free to move with the card and do not perforate it. More detailed information as to the punch structure may be had by 65 reference to United States Letters Patent No. 1,305,557, which mechanism has here 70 been selected to represent the operation of the present invention.

The solenoid 10 is included in a circuit having a conductor 20 connected to a contactor 21 which is oppositely disposed with respect to a contact 22 connected by a conductor 23 to a contact 24. The contactor 21 is arranged to be operated by the ordinary 75 actuation of a key 25 of a typewriter 26, this key 25, as here shown, being one of the number keys of the typewriter. Oppositely disposed with respect to the contact 24 is a contactor 27 connected to the common return conductor 28 of the circuit which includes a 80 rheostat 30, a switch 31 and a generator 32.

The foregoing circuit may be taken as any 85 one of the typewriter number key control circuits of Fig. 3 and since the contactor 27 is in the common return of all circuits, the operation of any circuit typewriter number key when this contactor 27 is closed, will 90 cause the circuit corresponding to that typewriter number key to close and thus set the punch corresponding to the actuated key 25. For example, if the number "8" key of the typewriter is actuated, its circuit will be closed and punch number "8" in the punch mechanism will be set to punch a hole in the 95 100

"8" position of the column over which the punch carriage is located.

For the purpose of automatically controlling the punch selecting means to perforate only predetermined columnar typewritten matter on the cards, the contactor 27 carries an actuating roller 33 which is in the path of movement of one face of a selecting bar 34. In the present instance, this bar is square in cross section so that it may be provided with four control surfaces though it will be understood the invention is not limited to this number of control surfaces but comprehends the use of a bar of polygonal section any face of which may be used for control purposes. In Figs. 1 and 4, the bar is shown as provided with four control surfaces while in Fig. 2 it is shown as provided with two control surfaces. One of the surfaces may be high or low throughout the whole length of the bar as is obvious. As here shown this selecting bar 34 is mounted upon the carriage 35 of the typewriter while the contactor 27 and its associated parts are carried by the fixed frame 36 of the typewriter. It will thus be seen, as the typewriter carriage moves step by step across the machine, that the selecting bar 34 will likewise move beneath the contact roller 33.

In order to make automatic selection of the columnar typewritten matter columns to be perforated on the card, the control faces of the bar 34 are provided with dwells 37 formed by recesses 38 cut respectively transversely in the faces of the bar 34. The arrangement of the bar with respect to the contact roller 33 is such that when a dwell 37 engages the roller 33, it will move the contactor 27 against the contact 24, but when a recess 38 arrives opposite to the roller 33 no movement of the contactor 27 will take place because the depth of the recess receives the roller 33 without imparting movement to it. Therefore, by arranging the dwells 37 at predetermined locations along the selecting bar 34 and having such dwells of predetermined length, one column of the card or several successive columns of the card are automatically selected for punching. Since different card groups may require different column punching from other card groups, the bar 34 has each face provided with differently arranged dwells and in this way a predetermined card punching is made for each group of cards. The bar 34 is mounted in brackets 40 for turning movement and has a hand wheel 41 by which it can be given the necessary partial rotation to bring a face into operative position and in which position the bar 34 is firmly held by a detent spring 42.

In order to lessen trouble incident to sparking at the contacts, a condenser 43, of suitable capacity, bridges the circuit at the required location.

Additional contactor operated circuit

70 closers are provided, one, 44, being arranged to be operated by the carriage return manual control key 45 of the machine; another 46 for skip purposes; another 47 for manual control of the punch and typewriter carriage return and being arranged in parallel with the circuit closer 48 which serves to bring about the automatic return of the punch carriage. The typewriter space bar is shown by reference 50.

75 In Fig. 3, the circuit closers including the contactors 27 are numbered to correspond to the number positions of a card column and while but two keys 25 are shown in this diagram, it is to be understood that there is a key 25 for each closer and the omission is made only for simplification of the drawings.

80 The operation is as follows: The selecting bar 34 is first set to bring the face, which has dwells 37 arranged to produce a card perforation arrangement corresponding to the group data to be listed or recorded by the separate controlling machine, in this instance a typewriter, into position to engage the contact making roller 33. In the selected position, the bar 34 is held by the spring 42 so that it cannot turn or be otherwise displaced during the operating cycle. The carriage 35 is moved to its starting position and the typewriter then operated in the usual manner so 85 that its carriage 35 travels step by step across the machine and therefore simultaneously moves the selecting bar 34 past the roller 33. During its travel the successive dwells 37 shift the roller 33 to close the contactor 27, which is common to all of the circuits, so 90 that the operation of any number key 25 will close the circuit of the key operated and thus make a set-up of the punch controlled by that circuit. When a recess 38 is opposite the roller 33, the common circuit closer remains open and hence the operation of any number key will not cause any punch set-up to be made. In this way, the typewriter functions in the ordinary way making a record of the 95 data typed, and only that part of the typewritten matter is perforated which has been previously selected by the choice of selecting bar face. While the present arrangement embodies a punch set-up from number keys 100 of the typewriter it is obvious that similar control can be had by arranging for contact operation by letter keys or any other characters.

105 While the foregoing description has referred specifically to a typewriter, it is to be understood that such reference is merely 110 illustrative of one application of the invention because broadly the invention is applicable to many other machines and where in the claims the term "recording machine" 115 occurs, it is to be taken as generic, meaning a typewriter, a tabulating machine, a book-keeping machine, or any other machine capable of co-ordination with a card per- 120 125 130

forating mechanism through the medium of the present invention.

Having thus described our invention, we claim:

5 1. In the combination of a recording mechanism comprising a carriage and a punching mechanism; means for causing a set-up to be made in the punching mechanism as a set-up is made in the recording 70
10 mechanism, a bar supported on said carriage for movement therewith, and means on the bar for controlling the effectivity of said set-up causing means.

15 2. In the combination of a recording mechanism comprising a carriage and a punching mechanism; means for causing a set-up to be made in the punching mechanism as a set-up is made in the recording 75
20 mechanism, a bar supported on said carriage for movement therewith, and high and low points on a face of said bar for controlling the effectivity of said set-up causing means.

25 3. In the combination of a recording mechanism comprising a carriage and a punching mechanism; means for causing a set-up to be made in the punching mechanism as a set-up is made in the recording 80
30 mechanism, a bar mounted for movement with said carriage, and high and low portions of different lengths on said bar for controlling the effectivity of said set-up causing means for variable extents of time.

35 4. In the combination of a recording mechanism comprising a carriage and a punching mechanism; means for causing a set-up to be made in the punching mechanism as a set-up is made in the recording 85
40 mechanism, a rotatably mounted bar on said carriage, and means on different sides of said bar for controlling the effectivity of said set-up causing means differently as may be predetermined.

45 5. The combination with a recording machine comprising a carriage and a key board; of punches, an electro-magnet for each punch 90
50 for controlling it for operation; a circuit closer for each key to energize a magnet when its corresponding key is depressed, a common circuit closer for all of said magnets, and a bar movable with said carriage for opening and closing said common circuit closer for predetermined positions of the carriage.

55 6. The combination with a recording machine comprising a carriage and a key board; of punches, an electro-magnet for each punch 95
60 for controlling it for operation, a circuit closer for each key to energize a magnet when its corresponding key is depressed, a common circuit closer for all of said magnets, and a bar movable with said carriage and provided with high and low portions for opening and closing said common circuit

closer for predetermined positions of the carriage.

7. The combination with a recording machine comprising a carriage and a key board; of punches, an electro-magnet for each punch 70
75 for controlling it for operation, a circuit closer for each key to energize a magnet when its corresponding key is depressed, a common circuit closer for all of said magnets, and a bar movable with said carriage and provided with high and low portions of different lengths for opening and closing said circuits for different positions of the carriage and for maintaining said circuits opened and closed for different extents of 80
85 movement of said carriage.

8. In the combination of a recording machine having a carriage, and a card-perforating machine controlled by said recording machine; means traveling with the carriage of 85
90 the recording machine for repeatedly making and breaking the connection to the perforating machine.

9. In the combination of a recording machine having a carriage, and a card-perforating machine, means for causing a set-up to be made in the perforating machine as matter is being recorded in the recording machine, and means carried by the carriage of the recording machine for disabling the aforesaid means so as to prevent the perforated card from forming a record of a predetermined portion of the matter recorded after the carriage has performed its function in the recording of other matter. 95

10. In the combination of a recording machine having a carriage, and a card-perforating machine, a system of punches in the perforating machine, punch-selecting devices, and actuating means which comprises relatively movable components mounted on the recording machine and by which desired action and inaction of those devices are made dependent on motion imparted to one of those components by the carriage of the recording 100
105 machine.

11. In the combination of a recording machine having a carriage, and a card-perforating machine, a system of punches in the perforating machine, and means to predetermine that a card-record of certain matter which is recorded by the recording machine and of which a card-record is not wanted shall not be punched, said means having relatively movable components mounted 110
115 on the recording machine and its action being dependent on movements imparted to one of those components by the carriage of the recording machine.

12. In the combination of a recording machine having a carriage, and a card-perforating machine, a system of punches in the perforating machine, and means which comprises relatively movable components mounted on the recording machine and by 120
125

which the punching of a record of matter recorded in any predetermined field on a record sheet is made dependent on motion imparted to one of said components by the carriage of the recording machine.

5 13. In the combination of a recording machine having a carriage, and a card-perforating machine, a system of punches in the perforating machine, and means which comprises a component mounted on the frame and another component mounted on and extending across the carriage of the recording machine and by which means the punching of a record of matter recorded in any predetermined field on a record sheet is made dependent on movement with the carriage of the latter component and its action on the other.

20 14. In the combination of a recording machine having a carriage, and a card-perforating machine, a system of punches in the punching machine, and means which comprises a component mounted on the frame and another component mounted on and extending across the carriage of the recording machine, the latter component including formations corresponding to different fields in which matter is recorded on a record-sheet, and by which means punching of a record of 25 matter recorded in any predetermined field wherever on the sheet that field may be is made avoidable.

25 15. In the combination of a recording machine having a carriage, and a card-perforating machine, a system of punches in the perforating machine and means which comprises a component mounted on the frame and another component mounted on the carriage of the recording machine, one of these 30 components crossing the other and being approximately as long as the carriage is wide and including formations corresponding to different fields in which matter is recorded on a record-sheet, and by which means the punching of a record of matter recorded in any predetermined field wherever on the record-sheet that field may be is made avoidable.

35 Signed at New York, county of New York, State of New York, this 17th day of August, 1926.
